UNITED STATES PATENT OFFICE.

JAMES FLEMING LOW, OF TORONTO, ONTARIO, CANADA.

PULP-SUCTION DIE.

Application filed April 23, 1928. Serial No. 272,182.

This invention relates to an improved pulp suction die, as described in the present specification and illustrated in the accompanying drawings which form part of same.

5 The invention consists essentially of the novel features pointed out broadly and specifically in the claims for novelty following a description containing an explanation in detail of an acceptable form of the invention.

10 The objects of the invention are to construct an efficient die, simple in construction and of manufacture; to design a die that is not easily plugged and that may be easily 15 cleaned and readily assembled to the die holder or vacuum chamber; and generally to provide an economical die capable of accomplishing the aforesaid purposes.

15 This die is adapted to be used in such machines as are now known to the art and is particularly adaptable to the vacuum chamber described in a former patent application filed October 31, 1927, as Serial No. 230,021 and is also an improvement over the die described in the said application.

20 In the drawings, Figure 1 is a fragmentary plan view of the die assembled.

Figure 2 is a perspective view of one of the segments in the die.

25 Figure 3 is a fragmentary cross sectional view showing the die assembled in any of the usual die boxes.

Figure 4 is a fragmentary plan view of Figure 2.

30 Like numerals of reference indicate corresponding parts in the various figures.

Referring to the drawings, 10 is the die complete consisting of the two end clamping pieces 11 held in position by the bolts 12 hav-

40 ing the countersunk heads 13 and nuts 13A countersunk in the openings 14 formed in the clamping pieces 11, and the corrugated segments or strips 16 held in place between the clamping pieces 11. The corrugated seg-

45 ments 15 have regularly spaced holes 16 punched therethrough through which the bolts 12 are inserted, thus serving to prevent any end motion of the segments, the bolts 12 fitting snugly through the holes 16. The upper edge 17 may be given any shape so as

50 to give the desired shape to the article being formed on the die. The segments 15 are corrugated in such a manner that the ridges or corrugations will be normal to the upper face of the die, that is vertical to the longitudinal axis of said segments, and are placed side by

side so that the points 18 of the corrugations in the segments will coincide with said points in the neighbouring segment, and thus small cells or openings 19 will be formed between 60 each of the segments through which the vacuum will act to draw the moisture from the die and leave the pulp substance deposited on the upper edge 17.

65 The chief advantage in this form of die is that the most minute particles of pulp are deposited on the upper edge of the corrugations, as the openings or cells 19 are very small and prevent the pieces from being drawn into said openings by suction. Another advantage is that any strips of pulp will be prevented from entering the openings as sometimes happens in the case of laminated dies in which strips are spaced one from another by shims or spacers. It will be noted that 75 the points 18 of the corrugations are slightly rounded so as to present a proper bearing space against which the neighbouring segment or corrugated strip may bear.

70 In Figure 3, the die 10 is shown as assembled in the die box 22 and the relieved portion in the upper edge 17 of the segments or corrugated strips is shown as at 20. It is to be understood that the edge 17 may be given such a profile as to form any of the desired 85 shapes. In the drawings the thickness of the corrugated strips are exaggerated considerably for the sake of clearness. It is to be noted that the corrugations are so formed that the openings 19 will be very small, that 90 is approximately the same as a very fine screen, the strips themselves being in the neighbourhood of from .010 to .015 of an inch in thickness, or of a greater thickness if found advisable.

95

What I claim is:

1. In a pulp suction die a plurality of vertically corrugated sheets drawn together in point to point contact and set in a suction box and forming a mould bed at the upper 100 ends and water passages therefrom.

2. In a pulp suction die, a plurality of vertically corrugated sheets clamped together and spaced by the corrugations at intervals, clamping bars, and a suction box containing 105 said sheets and bars.

3. In a pulp suction die, a suction box and a matrix formed of laminae spaced by contact and retaining bars and bolts.

4. In a pulp suction die, a suction box and a matrix comprising a lamination wherein the laminae are ridged to form water passages 110

from the moulds and clamping bars and bolts.

5. In a pulp suction die a matrix comprising a plurality of corrugated sheets having angular points meeting angular points and bolt holes in alignment, bounding walls having bolt and nut recesses and bolts extending through said bolt holes and having their heads and nuts countersunk in said recesses.

6. In a pulp suction die, a plurality of corrugated metal strips forming on one edge 10 the configuring wall of said die and having

the points of corrugation in said metal strips bearing one against the other, a pair of metal bars terminating the die on two sides thereof, holes through said corrugated strips and 15 through said metal bars, bolts engaging said holes and anchored in said bars and forming means of releasably locking said strips in their spaced relation between said bars.

Signed at the city of Toronto, this 8th day 20 of February, 1928.

JAMES FLEMING LOW.
